WILLIAM G. CROSS, OF SENECA FALLS, NEW YORK.

MOTIVE-FLUID MIXER FOR INTERNAL-COMBUSTION ENGINES.

1,030,388.

Specification of Letters Patent. Patented June 25, 1912.

Application filed October 24, 1908. Serial No. 459,333.

To all whom it may concern:

Be it known that I, WILLIAM G. CROSS, of Seneca Falls, in the county of Seneca and State of New York, have invented a certain 5 new and useful Motive-Fluid Mixer for Internal-Combustion Engines, of which the following is a specification.

My invention has for its object the production of a motive-fluid mixer for internal- 10 combustion engines, by means of which the amount of combustible fluid to be mixed with air in the formation of each charge of motive-fluid is positively controlled; and the invention consists in the combinations and 15 constructions hereinafter set forth and claimed.

In describing my invention reference is had to the accompanying drawing in which like characters designate corresponding 20 parts in all the views.

Figure 1 is an end view of a vaporizer embodying my invention and connections thereto to a movable part of the engine to which it is connected. Figs. 2 and 3 are 25 sectional views taken at right angles to each other, a mixing chamber being shown in Fig. 3. Fig. 4, is a sectional view similar to Fig. 2 showing the valve in a different position.

30 My motive-fluid mixer comprises means for measuring the amount of combustible fluid, as a gas, a liquid hydrocarbon or alcohol, to be mixed with air in forming each charge of motive fluid, and for cutting off 35 the air and fluid to be mixed with the air at the same time, so that the proportion of air and fluid to be mixed is always the same irrespective of whether the charge is a large or a small one.

40 As here illustrated my motive-fluid mixer is constructed to vaporize a liquid as a hydro-carbon or alcohol; and it includes a delivering device comprising a case 1 and a movable valve 2, in the case. The case 1 is 45 preferably of cylindrical form and is formed with laterally extending bosses or nipples 3, 4, designed to be connected, respectively, to the cylinder of an internal-combustion engine and the outlet conduit of the fluid 50 supply reservoir, the nipple 3 being shown in Fig. 3 as connected to a conduit 30 which constitutes a vaporizing or mixing chamber. The nipple 3 is formed with an air outlet 55 passage 5 and with the outlet passage 6 for the liquid to be vaporized, and the nipple 4 is formed with an inlet passage 7 for the

liquid to be vaporized, said inlet passage 7 being here shown as located about diametrically opposite to the passage 6. The case 1, as here shown, is formed in two sections, 60 each section being formed with flanges 8 engaged with each other and held together by clamps 9 passing transversely through the flanges 8, and by dowel pins 10 provided on one flange 8 and extending into openings in 65 the other.

The valve 2, is formed with an air-passage and with a transfer passage for the liquid to be mixed with air. These passages are movable into and out of registration with the 70 passages 5, 6 of the case during the formation of each charge, and as here shown said valve is journaled in the case and oscillates therein, and is formed with an axial air passage 11 communicating with the outer air 75 and having a radially-extending branch 12 movable into and out of registration with the air passage 5 of the case; and said valve 2 is also formed with an angular transfer passage 13 extending therethrough and 80 opening through opposite sides thereof, one end of said passage being movable into and out of registration with the inlet passage 7 for the liquid to be vaporized and the other end of the said passage being movable into 85 and out of registration with the exit passage 6 for such liquid, one end of the passage 13 being out of registration with the passage 7 while the other end is in registration with the passage 6 or vice versa. The valve 2 is 90 oscillated, by a movable part of the engine, not illustrated, to which this vaporizer is attached, and, as here shown, it is provided with a rock arm 14 connected by a link 15, to a movable part of the engine not shown, 95 this link 15 being slidably connected at 16 to the rock arm 14 in order that the extent of movement of the valve piece may be adjusted in order to vary the volumes of the charges, by shifting the link 15 toward and 100 from the axis of the valve. When the arm 14 oscillates to its fullest extent, the passage 12 will register squarely with the passage 5 while the transfer passage 13 will register squarely with the passage 6, and when the 105 passages 12 and 13 are out of register, respectively, with the passages 5 and 6, the transfer passage 13 registers with the inlet passage 7; and when the extent of the movement of the arm 14 is lessened, said passages 12 and 13 will not register exactly 110 with the passages 5 and 6, and 7, so that a

smaller charge is formed containing the same proportion of liquid and air as the larger charge.

Although the nipple 3 in which are formed the air and liquid outlet passages 5 and 6 is here shown as extending upwardly, and the nipple 4 in which is formed the inlet 7 for the liquid as extending downwardly, it is obvious that said passages 10 may be arranged in any desired positions, their positions being dependent in some instances upon the amount of fall between the supply tank and the vaporizer.

In operation, during the formation of each charge, the valve moves in one direction so that the transfer passage 13 of the valve 2 registers with the inlet passage 7 of the case for permitting the liquid to flow into the transfer passage; the valve then 20 moves in the reverse direction carrying the transfer passage 13 out of register with the passage 7 and bringing said transfer passage 13 and the air passage 12 into registration, respectively, with the air and liquid 25 outlet passages 6 and 5.

Owing to the fact that the valve shuts off the air and combustible fluid passages during the formation of each charge, back fire is prevented.

30 What I claim is:

1. A motive-fluid mixer formed with a transfer passage for the fluid to be mixed with gas to form a charge of motive fluid and with a passage for the gas, said passages having inlets and exits, and means operable once during the formation of each charge for opening the exits of said passages and closing said exits simultaneously, and for opening and closing the inlet of the 40 transfer passage alternately with the opening and closing of said exits, substantially as and for the purpose described.

2. A motive-fluid mixer for internal combustion engines having a mixing chamber, 45 inlet passages for the combustible fluid and gas to be mixed to form the motive fluid, a transfer passage interposed between the inlet passage for the combustible fluid and the mixing chamber, and means operable once during the formation of each charge 50 for simultaneously opening and closing the gas passage and the outlet end of the transfer passage and for opening and closing the inlet end of the transfer passage alternately 55 with the opening and closing of the outlet end thereof, substantially as and for the purpose described.

3. A motive-fluid mixer for internal combustion engines having a mixing chamber, 60 and an inlet passage for the combustible fluid, and a movable member movable between the inlet passage and the mixing chamber and formed with a gas passage and with a transfer passage for the combustible fluid, said member being movable once

during the formation of each charge for carrying the transfer passage first into registration with the inlet passage for the combustible fluid then out of registration with said inlet passage and into communication 70 with the mixing chamber, the gas and transfer passages being relatively arranged to be carried into and out of communication with the mixing chamber at the same time, substantially as and for the purpose specified. 75

4. A motive-fluid delivering device for internal combustion engines having outlet passages for the air and combustible fluid to be mixed with air and inlet passages for the air and such fluid, a transfer passage 80 interposed between the inlet and outlet passages for the combustible fluid, and means for opening and closing said outlet passages alternately with the opening and closing of the inlet passage for the combustible fluid 85 whereby the combustible fluid flows into the transfer passage and after the inlet passage for the fluid has been closed, the fluid in the transfer passage is drawn from the transfer passage through the outlet passage for 90 combustible fluid, substantially as and for the purpose set forth.

5. A motive-fluid delivering device for internal combustion engines, such device having inlet and outlet passages for the air 95 and for the combustible fluid, and the device including relatively fixed and movable members, the fixed member being formed with such outlet passages and with the inlet passage for the motive fluid and the movable 100 member being movable between said outlet and inlet passages for opening and closing said passages and said movable member being formed with an air passage and with a transfer passage arranged to register simultaneously with the air outlet and fluid outlet passages respectively, the air passage communicating with the air inlet passage of the device and the transfer passage being also adapted to register with the inlet passage 110 for the motive fluid, when out of registration with the outlet passage for the motive fluid, the transfer passage being carried by the movable member alternately into and out of registration with the inlet and outlet 115 passages for the motive fluid, and means for moving said member once during the formation of each charge, substantially as and for the purpose specified. 120

6. A motive-fluid mixer for internal-combustion engines comprising a case, a movable valve in the case, the case being formed with an outlet passage for the liquid and an outlet passage for the gas to be mixed with the liquid and with an inlet passage for the liquid, one of said parts being also formed with an inlet passage for the gas, and the valve having liquid and gas passages movable at the same time into and out of registration, respectively, with the liquid outlet 125 130

passage and the gas outlet passage of the case, the liquid passage of the valve extending transversely of the valve and being also movable into registration with the liquid inlet passage of the case when moving out of registration with the liquid outlet passage of the case, and means for moving the valve in the case for bringing the various passages into and out of registration once during the formation of each charge of motive-fluid, substantially as and for the purpose specified.

7. A motive-fluid mixer for internal-combustion engines comprising a case having gas and liquid outlet passages, a movable valve in the case, the case being formed with an outlet passage for the gas and also with an inlet passage for the liquid located about diametrically opposite to the liquid outlet passage of the case, and the valve being journaled in the case and having a transfer passage extending transversely therethrough and an air inlet passage extending through one end and through one side thereof, one end of the transfer passage being movable into and out of registration with the liquid outlet passage of the case while the gas passage of the valve is moving into and out of registration with the gas outlet passage of the case, and the other end of the transfer passage being movable into and out of registration with the liquid inlet passage of the case and being out of registration therewith when said one end is registering with the liquid outlet passage, and means for oscillating the valve in the case once during the formation of each charge of motive-fluid, substantially as and for the purpose set forth.

40 8. A motive-fluid mixer for internal combustion engines having a mixing chamber, inlet passages for the combustible fluid and gas to be mixed to form the motive fluid, a transfer passage interposed between the inlet passage for the combustible fluid and the mixing chamber, means operable once during the formation of each charge for simultaneously opening and closing the gas passage and the outlet end of the transfer passage and for opening and closing the inlet end of the transfer passage alternately with the opening and closing of the outlet end thereof, and means for varying the extent to which the various passages are opened for varying the volumes of the charge of motive fluid without varying the portion of the ingredients, substantially as and for the purpose specified.

60 9. A motive-fluid mixer for internal combustion engines having a mixing chamber, and an inlet passage for the combustible fluid, a movable member movable between the inlet passage and the mixing chamber formed with a gas passage and with a transfer passage for the combustible fluid, said

member being movable once during the formation of each charge for carrying the transfer passage first into registration with the inlet passage for the combustible fluid then out of registration with said inlet passage and into communication with the mixing chamber, the gas and transfer passages being relatively arranged to be carried into and out of communication with the mixing chamber at the same time, and means for varying the amount of movement of the movable member for varying the volume of the charges formed in the mixing chamber without varying the proportion of the ingredients thereof, substantially as and for the purpose set forth. 70

10. A motive-fluid delivering device for internal combustion engines having outlet passages for the air and combustible fluid to be mixed with air and inlet passages for the air and such fluid, a transfer passage interposed between the inlet and outlet passages for the combustible fluid, means operable once during the formation of each charge for opening and closing said outlet 85 passages alternately with the opening and closing of the inlet passage for the combustible fluid whereby the combustible fluid flows into the transfer passage and after the inlet passage for the fluid has been closed the fluid in the transfer passage is drawn from the transfer passage through the outlet passage for combustible fluid and means for varying the extent to which said passages are opened by the first-mentioned 90 means, substantially as and for the purpose set forth. 95

11. A motive-fluid delivering device for internal combustion engines, the device having inlet and outlet passages for the air and for the combustible fluid, the device comprising relatively fixed and movable members, the fixed member being formed with the outlet passages for the air and the combustible fluid and with the inlet passage for such fluid, and the movable member being movable between said inlet passage for the combustible fluid and said outlet passages for opening and closing said passages, and the movable member being formed with an air 110 passage communicating with the inlet air passage and with a transfer passage, the transfer passage being carried by the movable member alternately into and out of registration with the inlet and outlet passages 115 for the combustible fluid, and the air passage being arranged to be carried into register with the air outlet passage when the transfer passage registers with the fluid outlet passage, the air passage and the transfer 120 passage of the movable member being closed by the fixed member when the transfer passage is not in registration with the inlet or outlet passages for the combustible fluid, means for moving the movable member once 130

during the formation of each charge, and means for varying the amount of movement of said member in order to vary the extent to which the transfer passage and air passage of the movable member are opened to the inlet and outlet passages with which they register, substantially as and for the purpose specified.

12. A motive-fluid mixer for internal combustion engines comprising a case, a movable valve in the case, the case being formed with an outlet passage for the liquid and an outlet passage for the gas to be mixed with the liquid and with an inlet passage for the liquid, one of said parts being also formed with an inlet passage for the gas, and the valve having liquid and gas passages movable at the same time into and out of registration, respectively, with the liquid outlet passage and the gas outlet passage of the case, the

liquid passage of the valve being also movable into registration with the liquid inlet passage of the case when moving out of registration with the liquid outlet passage of the case, means for moving the valve in the case for bringing the various passages into and out of registration once during the formation of each charge of motive fluid, and means for varying the extent of movement of the valve, substantially as and for the purpose described.

In testimony whereof, I have hereunto signed my name in the presence of two attesting witnesses, at Seneca Falls, in the county of Seneca, in the State of New York, this 25th day of September, 1908.

WILLIAM G. CROSS.
